WHEELED CART

Harold Bloomfield and Melvin F. Roberts, Chicago, Ill.,
assignors to Bloomfield Industries, Inc., Chicago, Ill.

Filed Sept. 8, 1970, Ser. No. 24,874

Term of patent 14 years

Int. Cl. D12—02

U.S. Cl. D14—3

FIG. 1 is a perspective view of a wheeled cart showing our new design with the trays removed, the opposite side being substantially the same;

FIG. 2 is an end view thereof, the opposite end being substantially the same;

FIG. 3 is a perspective view similar to FIG. 1 but showing the trays upon the shelves.

We claim:

The ornamental design for a wheeled cart, as shown and described.
